UNITED STATES PATENT OFFICE.

FRANK A. BURKHART, OF READING, PENNSYLVANIA.

DESIGN FOR A FOUNTAIN-BRUSH BACK.

45,328.

Specification for Design.

Patented Mar. 3, 1914.

Application filed October 2, 1913. Serial No. 793,076. Term of patent 7 years.

To all whom it may concern:

Be it known that I, FRANK A. BURKHART, a citizen of the United States, residing at Reading, in the county of Berks and State of Pennsylvania, have invented a new, original, and ornamental Design for a Fountain-Brush Back, of which the following is a specification, reference being had to the accompanying drawing, forming part thereof.

The figure is a perspective view of a fountain brush, showing my new design.

I claim:

The ornamental design for a fountain brush back, as shown.

In testimony whereof I affix my signature in presence of two witnesses.

FRANK A. BURKHART.

Witnesses:

D. M. STEWART,
A. M. KURTZ.
